MECHANISM FOR OPERATING METAL-
LURGICAL FURNACE DOORS

Paul B. Tonnar, Cleveland, Ohio

Application August 6, 1932, Serial No. 627,796

5 Claims. (Cl. 268—19)

This invention relates to an apparatus for raising and lowering the doors of a metallurgical furnace and more particularly to improved means for operating the furnace doors of an open hearth furnace.

Heretofore the apparatus which has been most commonly used for raising and lowering furnace doors has consisted mainly of a hydraulically operated and controlled type. The 10 use of such apparatus called for an extensive outlay of pipes, valves, pumps and related equipment and in those installations where water was used as the fluid medium it was necessary to provide additional means to prevent the same 15 from freezing during the winter season. Such system, on the whole, was costly to install, and difficult and expensive to maintain. In other cases, the apparatus for raising and lowering the doors consisted largely of a winch and speed 20 reducer driven by an electrical motor, one being provided for each door of the furnace. Such installations were undesirable in view of the initial and maintenance costs, and the duplication of motors and speed reducers.

25 According to the present invention, I have been able to develop a device which solves the aforesaid problems and one which is capable of operating a plurality of doors through a single driven means.

30 Briefly stated the illustrated embodiment of this invention comprises a shaft driven through suitable driving means and upon which is rotatably mounted a plurality of spaced cable winding sheaves. Disposed on each side of the 35 sheaves are suitable magnetic means, one of which causes the sheave to rotate with the shaft, and the other magnetic means prevents the rotation of the sheave, and maintains the same in a fixed position during certain periods in the 40 operation of the furnace doors. Cables are adapted to pass once around the winding sheaves, one end of such cables being secured to the upper portion of the open hearth door, the 45 opposite end being suitably counterweighted to offset the weight of the door.

Numerous advantageous features more or less ancillary to the foregoing and which are not specifically set forth at this time will become 50 more apparent as the detailed description of this invention continues, which, considered in conjunction with the drawings sets forth the preferred embodiment of my invention and wherein:

55 Figure 1 is a top plan view which diagrammati-

cally illustrates the adaptation of my invention to an open hearth furnace.

Figure 2 is a side elevation partly broken away of the device illustrated in Figure 1.

Figure 3 is a sectional elevation taken on the 60 line 3—3 of Figure 1.

Figure 4 is a top plan view of the actuating mechanism for raising and lowering a plurality of doors.

Figure 5 is a side elevational view taken on 65 the line 5—5 of Figure 4.

Figure 6 is an enlarged detailed view partly in section of one of the door actuating units.

Figure 7 is a modified form of the door actuating unit.

With reference to Figures 1, 2 and 3 there is diagrammatically illustrated an open hearth furnace 1 in which my invention has been incorporated. The open hearth furnace 1 has a plurality of doors 2 which are adapted to be 70 raised or lowered through the medium of suitable cables 3. These cables have one end secured to and extended from the door 2 upwardly and pass over deflecting sheaves 4, across the top of the furnace where they pass about deflecting sheaves 5, thence once around the winding sheave 6 of my cable actuating mechanism from thence upwardly and over deflecting sheaves 7 from which they depend, carrying on the end 75 thereof a counterweight. As such times as a door or a counterweight is disposed at their lowermost positions, the winding sheave 6 may be allowed to continue in rotation without fear of overwind as this continued rotation produces a slackening effect in cable 3 about the periphery of winding sheave 6, of the cable actuating mechanism, thereby preventing further travel of the cable 3 and precluding the necessity of providing limit switches controlling the driving means.

The cable actuating mechanism for raising a 95 plurality of doors is illustrated more in detail in Figures 4 and 5 of the drawings and comprises a geared speed reducer 9 built integral with a reversible electric motor 10. This unit is adapted to drive a continuous shaft 11, through the 100 medium of a flanged coupling 12. The shaft 11 is supported in suitable bearings 12a disposed upon the upper surfaces of transverse channel beams 13. Mounted on the shaft 11 and free to partake of movement relative to said shaft are a plurality 105 of winding sheaves 6. These sheaves are preferably disposed in spaced relation and are adapted to engage cables 3 for raising and lowering the furnace doors.

Disposed in opposed relation on opposite sides 110

of the sheaves 6 are magnetic field units 15 and 16. The magnetic unit 15 is substantially cylindrical in shape having an axial extension 17 formed thereon. The magnet unit 15 is keyed to the shaft 11 and rotates therewith. The extension 17 carries a collector ring 18 which contacts in any suitable manner with brushes (not shown) for conveying an electric current thereto from any suitable source. The collector ring 18 and the brushes associated therewith are preferably encased in a sheet metal housing 23 supported on brackets 24 secured to the channels 13. Carried in suitable recesses 20 disposed in the unit 15 are a plurality of electromagnet coils 21 which have associated therewith friction surfaces 25 engageable with the side face of sheaves 6. When the coils 21 are energized the body of the winding sheave 6 constitutes an armature and is attracted to the electromagnet causing the friction surfaces 25 to engage the side face of the sheave and to rotate the sheave with the magnet unit which is secured to the driven shaft 11.

The magnet unit 16 which is disposed on the opposite side of the sheave 6 is substantially of the same construction as the rotating unit 15. This unit includes a plurality of electromagnet coils 26 which carry friction surfaces 27, the latter being adapted to engage the side face opposite to that which is engaged by the friction surfaces 25. The coils 26 may be supplied with an electrical current in any convenient manner and from any source desired. The unit 16 is preferably immovably secured to the supporting channels 13 as at 28. The unit 16 is effective in maintaining the door in any desired position, within its limits of travel, without stopping the motor 10, by switching the energizing current from magnet coils 20 to magnet coils 26.

The unit 16 may also serve as a brake to prevent jarring of the door or counterweight at their extreme limits of travel by only slightly energizing magnet coils 26 while coils 20 are receiving full or normal energizing current.

I have elected to describe only one unit in detail and as shown in Figures 4 and 5 a plurality of these door actuating units may be mounted on a single shaft. The shaft 11 may be rotated in either clockwise or counter-clockwise directions and through energization of the electromagnet coils 20 carried by the unit 15 the individual door operated thereby may be raised or lowered as desired.

With reference to Figure 7 there is illustrated a modified form of door actuating unit. In this embodiment there is substituted for the unit 16 a disk-like flange plate 30 carrying friction elements 31 adapted to engage the side face of the winding sheave 6. The flange plate is formed with an axial extension 32 which forms a bearing for the shaft 11. The plate 30 is preferably immovably secured to the supporting channels 13. A coil spring 33 carried by the unit 15 is disposed about the shaft 11 and normally holds the freely movable winding sheave 6 against the friction elements 31 when the magnet coils 20 carried by the unit 15 are deenergized. At such time as these coils are energized the attraction for the sheave 6 overcomes the force of the spring 33 and permits the sheave to rotate with the magnet unit 15.

Although the foregoing description is necessarily of a detailed character, I do not wish to be limited thereby other than by the appended claims.

I claim:

1. In an apparatus for raising and lowering the doors of a metallurgical furnace, a cable having one end thereof secured to the door and the opposite end secured to a counterweight, means for actuating the cable, comprising a driven shaft, a sheave rotatably mounted on said shaft, means including an electromagnet for operatively connecting said shaft and sheave, means for preventing rotative movement of said sheave, and means carried by said electromagnet for maintaining said sheave in engagement with said last named means. 80

2. In an apparatus for raising and lowering the doors of a metallurgical furnace, a cable having one end thereof secured to the door and the opposite end secured to a counter weight, means for actuating said cable, said means including a driven shaft, a member keyed to said shaft and rotatable therewith, means engaging said cable carried by said shaft and rotatable thereon, opposed magnetic units disposed about said shaft, one of said magnetic units when energized adapted to operatively associate said cable actuating means and said member to permit said cable engaging means to rotate with said shaft, the other of said magnetic units when energized adapted to serve as a brake unit. 90

3. In an apparatus for raising and lowering the doors of a metallurgical furnace, a cable having one end thereof secured to the door and the opposite end secured to a counterweight, means for actuating said cable, said means including a driven shaft, means engaging said cable rotatably mounted on said shaft, a member keyed to said shaft and rotatable therewith, magnetic means adapted to operatively associate said member and said cable engaging means to permit the cable engaging means to rotate with the shaft, and a fixed brake member disposed about said shaft and 105 in opposed relation to said magnetic means, said brake means including an electromagnet having a friction face disposed thereon. 110

4. In an apparatus for raising and lowering the doors of a metallurgical furnace, a cable having one end thereof secured to the door and the opposite end secured to a counterweight, means for actuating said cable, said means comprising a driven shaft, an electromagnet mounted on said shaft and rotatable therewith, a sheave 120 engaging said cable and rotatably mounted on said shaft in close proximity to said magnet, and means for energizing said electromagnet whereby the sheave will be rotated therewith and magnetic means mounted concentric with the shaft and 125 engageable with the face of the sheave, said magnetic means when energized adapted to prevent rotative movement of the sheave. 130

5. In an apparatus for raising and lowering the doors of a metallurgical furnace, a cable having one end thereof secured to the door and the opposite end secured to a counter weight, means for actuating said cable, said means comprising a driven shaft, an electromagnetic mounted on said shaft and rotatable therewith, a sheave 140 engaging said cable and rotatably mounted on said shaft in close proximity to said magnet, and means for energizing said electromagnet whereby the sheave will be rotated therewith and brake means mounted concentric with the shaft and 145 engageable with the face of the sheave for preventing rotative movement thereof. 150

PAUL B. TONNAR.
